H. G. GILLMOR,
RAIL ANCHOR,
APPLICATION FILED DEC. 12, 1917.

1,307,490.

Patented June 24, 1919.

UNITED STATES PATENT OFFICE.

HORATIO G. GILLMOR, OF WASHINGTON, DISTRICT OF COLUMBIA.

RAIL-ANCHOR.

1,307,430.

Specification of Letters Patent. Patented June 24, 1919.

Application filed December 12, 1917. Serial No. 203,775.

To all whom it may concern:

Be it known that I, HORATIO G. GILLMOR, a citizen of the United States, residing at Washington, in the District of Columbia, have invented certain new and useful Improvements in Rail-Anchors, of which the following is a specification.

My invention relates to a device for preventing the longitudinal creeping of railroad rails. Such devices are commonly called rail anchors, rail stays or anticreepers. The invention relates particularly to a device in two parts in which one or preferably both of the elements are resilient and strained by the application of the device to the rail so that retrograde movement of the rail, vibration or other accidental cause will not loosen the grip of the device upon the rail and hence diminish its holding power. A rail anchor is subject, not only to the stress caused by the tendency to forward or creeping movement in the rail, but also to vibration and to forces which operate at times to cause the rail to move in a direction the reverse of that tending to produce forward creep, which forces tend to move the device away from the tie against which it abuts and to loosen the grip of the parts one upon the other and of both upon the rail. Unequal expansion and contraction of the rail and parts due to changes in temperature also tend to reduce and destroy the holding power of the device.

The primary object of my invention is to provide a rail anchor comprising a plurality of coengaging elements which together grip the rail and are so constructed and arranged that forward or creeping movement of the rail produces the coaction of the elements whereby this tendency to creep is self-checked one or more of the elements being resilient and strained when applied to the rail so that vibration and changes in dimension of the material due to temperature changes are absorbed and any tendency of the parts of the device to loosen by reason of the retrograde relative movement is prevented.

A further object of the invention is to provide a rail anchor of the type in which

a rail base engaging yoke and a tie abutting rail bottom engaging shoe are employed which shall be reversible and effective in preventing movement of the rail in either direction. It is often necessary or desirable to prevent movement of the rail in either direction. Reversibility is an advantage in that it greatly reduces the possibility of incorrectly applying the device and permits application to be made from either side. In some cases it is advantageous or more convenient to apply a device of this character from one side of the rail rather than from the other side.

A further object of the invention is to provide a rail anchor which will be inexpensive to manufacture, strong and durable and at the same time light in weight. Weight is an important consideration both in the cost of manufacture and the cost of transportation.

The invention is illustrated in one embodiment in the accompanying drawings, in which:

Figure 1 is a side elevation, showing the device in operative position upon the rail.

Fig. 2 is a sectional elevation at the plane indicated by XX in Fig. 1, looking toward the tie against which the device abuts.

Fig. 3 is a plan view of the device in operative position upon the rail viewed from below the rail bottom.

Fig. 4 is a sectional view, at the plane indicated by XX in Fig. 1, showing the device in one of the positions assumed by the parts while the device is being applied to the rail.

Like characters of reference designate like parts in the several figures of the drawings. Referring to the drawings, A designates a railroad rail having a base flange B resting upon and supported by cross tie, one of which is designated by C. The rail anchor illustrated consisting of two coengaging elements, a tie abutting element or shoe D and a yoke E.

The tie abutting element or shoe D may be formed from a plate and is provided with two flanges F and F₁, either of which is adapted to bear against a cross tie C and has a bearing seat G between the flanges F and F₁. It is also provided with a tongue H.

at the end of which the portion I is turned upward to form a shoulder adapted to engage one edge of the rail base B. In the normal unstressed condition of the tie engaging element or shoe D the portion K will not be parallel to the tongue H of the shoe D but will stand at an angle thereto as illustrated in Fig. 4.

The yoke element E is adapted to extend 10 around the base of the rail and has an arm or jaw L adapted to engage the upper surface of the rail base B at one side of the rail and an arm M adapted to engage the upper surface of the rail base B at the other 15 side of the rail. The arms L and M are of unequal length the arm L being the longer. The body of the yoke element E extends transversely beneath the rail and is formed intermediate of the arms or jaws L and M 20 with a bend presenting a surface N which is adapted to engage with the bearing surface G of the shoe D.

In applying the device to the rail the longer arm L of the yoke element E is hooked over 25 one side of the rail base B and the tie abutting element or shoe D placed beneath the rail with the bearing G of the shoe D in engagement with the surface N of the yoke E and the yoke E then raised to the position 30 at which the arm M of the yoke E may be brought into engagement with the upper corner of the rail base B opposite to the arm L of the yoke E. To facilitate the application of the device the end of the arm M 35 is beveled or rounded at O. In this position of the parts the portion K of the shoe D will be about to begin to engage with the lower corner of the rail base B. The yoke is then moved forcibly transversely 40 of the rail by driving with a hammer or maul; and, when the yoke is so driven, both the yoke E and the shoe D will move transversely upon the rail, the arm M of the yoke E moving up upon the upper surface 45 of the rail base B and the portion K of the shoe D being forced downwardly with a tendency to flatten the shoe D against the bottom of the rail base B. During this transverse movement, the yoke E moves angularly in the transverse plane in relation 50 to the shoe D, the form of the bearing G of the shoe D and of the surface N of the yoke E permitting such movement. As the yoke E and shoe D are moved to the final 55 position shown in Figs. 1, 2 and 3 a strong pressure is caused to be exerted by the yoke and the shoe upon the rail so as to firmly grip the rail between the yoke E and the shoe D. During the transverse movement 60 of the parts the portion I at the end of the tongue H upon the shoe D moves in contact with the bottom of the rail base B, the tongue H being strained as necessary to permit this. When the final operative 65 position of the parts is reached the resil-

lency of the tongue H will cause the portion I to spring into the position shown in Figs. 1 and 2 with the portion I engaging the edge of the rail base B so that the parts are thus locked against reverse movement. 70

The direction in which the rail tends to move under the creeping stress is indicated by the arrow in Fig. 1 and is the direction referred to as forward. A forward creep of the rail A carries with it the yoke E and 75 shoe D until the flange F of the shoe D comes into contact with the tie C which is embedded in the ballast and therefore fixed in position. With the device in operative position upon the rail the rail base B will so generally be so firmly gripped between the shoe D and the yoke E that further tendency of the rail to forward creep will be prevented by this engagement of the flange F with the tie C. Should however, the grip be not sufficient to prevent such movement and slight further forward creep occur the arms L and M of the yoke E will be carried forward with the rail, while the body of the yoke E, engaging with its surface N the bearing G of the shoe D, will be held in position. This will cause the yoke E to move slightly angularly and assume the position indicated by the dotted lines in Fig. 1 and such action will increase 85 the grip of the parts upon the rail base B so that the creeping movement will thus be self-checked. On the other hand should there be any reverse or backward movement of the rail the parts will be carried with 90 the rail and the flange F will be carried out of contact with the tie. Even though the shoe D should during such reverse movement be held fixed the reverse movement would still be without effect on the 95 holding power of the device. The elastic relation between the parts and the positive locking of parts upon the rail by the engagement of the portion I of the shoe D with the edge of the rail base B prevents 100 entirely any loosening of the device upon the rail by reason of vibration, changes in dimension of the materials due to temperature, or any other accidental cause.

It will be readily understood that the tie 105 abutting flanges F and F₁ may be so placed that each may be in contact or almost in contact with faces of two adjacent ties, and the device thus made effective in preventing creeping movement of the rail in either 110 direction. The parts coact to check and prevent movement of the rail in the direction which has been referred to as backward 115 in the same manner and degree as they coact in checking and preventing forward 120 movement.

Should it become necessary to remove the device from the rail the portion I of the shoe D must first be forced downwardly so that the yoke and shoe may be driven trans-

ersely of the rail in a direction the reverse of that necessary in applying the device to the rail until the arm M of the yoke E is released from the rail base B and the yoke E may be dropped and the arm L may be removed from engagement with the other side of the rail base B.

While I have shown and described the invention in one embodiment modifications might be made without departure from the principles of the invention. Therefore, I do not wish to be understood as limiting the invention to the particular construction, arrangement and devices shown and described except so far as these limitations are specifically set forth in certain of the claims herein.

I claim and desire to secure by Letters Patent:

20 1. A shoe for rail anchors constructed with a tie engaging flange and means for interlocking with a rail base engaging yoke and provided with a resilient tongue terminating in a rail base edge engaging catch.

25 2. A shoe for rail anchors constructed from a plate and provided with means for interlocking with a rail base engaging yoke, a tie engaging flange and a flexible tongue having a locking projection adapted to engage one edge of the rail base.

30 3. A shoe for rail anchors constructed from a plate and formed with a bearing adapted to have rotational engagement with a rail base engaging yoke and provided with two flanges either of which may engage a tie.

40 4. A rail anchor, comprising a rail base engaging shoe having a bearing on the under side thereof and a tie abutting flange and a yoke having a portion arranged to bear upon said shoe underneath the rail base and a pair of terminal jaws adapted to rigidly engage the top of the rail base when said yoke is forcibly moved transversely of said rail base to effect the gripping action.

5. An anticreeper for rails, comprising a rail bottom engaging part provided with a bearing seat and with means for giving 50 said part a fixed position in the roadbed in opposition to the tendency of the rail to creep and a yoke having pivotal engagement with said bottom engaging part beneath the rail base and terminal gripping jaws 55 formed on said yoke for securing said anticreeper to the rail base, said yoke and bottom engaging part being adapted to be moved transversely on the rail base after being applied thereto whereby the said anticreeper may be tightened or loosened on the rail base.

6. A rail anchor, comprising two coengaging rail clamping elements, one of which is adapted to bear against a tie and the other to be free therefrom; said elements

being constructed so that they have pivotal engagement one with the other and that when the free member is moved transversely of the rail the rail base is gripped between the said coengaging rail clamping elements. 70

7. A rail anchor, comprising a rail bottom engaging shoe and a member bent to form a body portion adapted to engage said shoe and end arms for engaging the top surface of the rail base on either side of the rail 75 whereby to secure said rail anchor to the rail base, the said shoe and the said member cooperating to grip the rail base between them when said member is forcibly moved transversely of the rail base. 80

8. A rail anchor, comprising two coengaging rail clamping elements, one of which is adapted to bear against a tie and the other to be free therefrom; said elements being constructed so that they have pivotal engagement one with the other, one of said elements being resilient and strained when said elements are forcibly moved transversely of the rail base. 85

9. A rail anchor, comprising two coengaging rail clamping elements, one of which is adapted to bear against a tie and the other to be free therefrom; said elements being constructed so that they have pivotal engagement with each other, both of said 95 elements being resilient and strained when forcibly moved transversely of said rail base.

10. A rail anchor, comprising a rail embracing element extending around the base 100 of the rail and a resilient member having a bearing engaging pivotally with said rail embracing element, which is strained by the forced movement of said rail embracing member transversely in relation to the rail 105 base.

11. A rail anchor, comprising a rail embracing element extending around the base of the rail and a resilient rail bottom engaging member, having a tie abutting portion and a bearing having pivotal engagement with said rail embracing element, said rail bottom engaging member being strained and drawn into contact with the bottom of the rail base by forced movement of said 115 rail embracing element transversely on the rail base.

12. A rail anchor comprising a rail embracing element extending around the base of the rail and a resilient shoe which lies 120 under the base of the rail and in unstrained condition stands away from the bottom of the rail base but is adapted to be drawn up to the bottom of the rail base so as to provide a rigid shoe, with which said rail embracing element engages when said rail embracing element is forcibly moved transversely upon the rail base. 125

13. A device for preventing the creeping of rails, comprising two co-engaging rail

clamping elements, one of which is adapted to bear against a tie and the other to be out of contact therewith; said elements having interlocking pivotal engagement one with the other and co-operating to grip the rail base between them when forcibly moved transversely upon the rail base.

14. A rail anchor, comprising a rail embracing element extending around the base of the rail and a member which intervenes between the bottom of the rail base and said rail embracing element and is provided with a resilient tongue having a portion adapted to engage one edge of the rail base for locking the device in position upon the rail.

15. A rail anchor, comprising a yoke member adapted to extend around the base of the rail and a shoe, provided with a tie engaging portion, adapted to be embraced by said yoke and to be pressed up against the bottom of the rail base when said yoke is forcibly moved transversely upon the rail base.

16. A rail anchor, comprising a yoke adapted to extend around the base of the rail and a shoe which intervenes between the bottom of the rail base and said yoke and is provided with a tongue having a projection which automatically engages the edge of the rail base when said yoke and shoe are forcibly moved transversely of the rail base.

17. A rail anchor, comprising a yoke and a sheet metal shoe, bent so as to form a tie abutting flange and a bearing, embraced by said yoke and provided with a tongue formed with a projection adapted to bear upon one edge of the rail base.

18. A rail anchor, comprising a rail embracing element extending around the base of the rail and a resilient shoe adapted to lie under the base of the rail and in unstressed condition to be in contact therewith at opposite sides and having a tie abutting portion, said shoe being strained and drawn up into contact with the bottom of the rail base so as to provide a substantially rigid shoe by forced movement of said rail embracing element transversely on the rail base.

19. A rail anchor, comprising a member provided with a cylindrical bearing on the under side thereof adapted to lie along and in contact with the bottom of the rail base and a portion of which is flexible and adapted to bear against one edge of the rail base only at its extremity, said member being provided with a tie abutting flange, and a yoke extending around said rail base and said member so as to subject said member to a bending strain.

20. A rail anchor, comprising a member formed from a plate provided with a plurality of tie engaging flanges and a yoke adapted to extend around the base flange of the rail and said member so as to press said

member up against the bottom of the base flange of the rail.

21. A rail anchor, comprising a shoe formed from sheet metal adapted to lie beneath and in contact with the bottom of the rail base and with a portion which is flexible and adapted to engage an edge of the rail base at its extremity and a yoke adapted to extend around the rail base and said shoe and to press said shoe up against the bottom of the rail base.

22. A device for preventing the creeping of rails, comprising two co-engaging rail clamping elements, one of which is adapted to bear against a tie and the other to be free therefrom; said elements having interlocking engagement one with the other whereby the two said elements may be forced to move together transversely upon the rail base to effect the gripping action and may be locked in operative position upon the rail by the engagement of a portion of one of said elements with the rail base edge.

23. An anticreeper, comprising a rail embracing element extending around the base of the rail and a tie-engaging resilient member which engages the rail base, interlocks with said rail embracing element and is strained by the forced movement of said rail embracing element transversely upon the rail base.

24. A rail anchor, comprising a resilient, tie-engaging, shoe, which lies under the base of the rail and in the normal unstrained condition is partly away from and out of contact with the bottom of the rail base but is adapted to be drawn up into contact therewith so as to provide a substantially rigid shoe and a part having a body portion interlocking with said shoe and terminal jaws arranged so as to rigidly engage the top of the rail base when said part is forcibly moved transversely of said rail base and thereby strain said shoe and grip the rail base between said part and said shoe.

25. An anticreeper, comprising a yoke constructed with terminal jaws rigidly engaging the top of the rail base and a member constructed with a tie engaging portion, which interlocks and co-operates with said yoke to grip the rail base between them when forcibly moved transversely of the rail base, and is provided with means for locking the parts so as to prevent reverse transverse movement upon the rail base.

26. A rail anchor, comprising two co-engaging rail clamping elements, one of which is adapted to bear against a tie and the other to be out of contact therewith said elements being constructed so that they have pivotal engagement one with the other and that when forcibly moved transversely of the rail base said rail base is clamped between the said elements.

27. In a rail anchor, the combination of two rail clamping elements, one of which is constructed with terminal jaws rigidly engaging the top of the rail base and one of which is resilient and intervenes between said element first named and the rail bottom and is strained and caused to exert an up-

ward pressure which is distributed across the rail bottom when said elements are forcibly moved transversely upon the rail; one of said elements having means for engaging with a tie.

H. G. GILLMOR.
